No. 36,878.

Patented April 12, 1904.

UNITED STATES PATENT OFFICE.

CARL H. SEEGER, OF MANITOWOC, WISCONSIN.

DESIGN FOR A DENTAL-TOOL HANDLE.

SPECIFICATION forming part of Design No. 36,878, dated April 12, 1904.

Application filed February 17, 1904. Serial No. 193,956. Term of patent 14 years.

To all whom it may concern:

Be it known that I, CARL H. SEEGER, a citizen of the United States, residing at Manitowoc, in the county of Manitowoc and State of Wisconsin, have invented a new, original, and ornamental Design for Dental-Tool Handles, of which the following is a specification, reference being had to the accompanying drawings, forming a part thereof.

10 In the said drawings, Figure 1 is a plan

view, and Fig. 2 is an end view, of a dental-tool handle, illustrating my said design.

I claim—

The ornamental design for a dental-tool handle substantially as herein shown.

CARL H. SEEGER.
